J. E. HUGHEL.
CONTAINER.
FILED OCT. 11, 1919

1,447,473.

UNITED STATES PATENT OFFICE.

JESSIE E. HUDGEL, OF MISSOURI VALLEY, IOWA.

CONTAINER.

Application filed October 11, 1919. Serial No. 329,930.

To all whom it may concern:

Be it known that I, JESSIE E. HUDGEL, a citizen of the United States, residing at Missouri Valley, in the county of Harrison and 5 State of Iowa, have invented certain new and useful Improvements in Containers, of which the following is a specification, reference being had to the accompanying drawings.

10 This invention relates to certain improvements in containers, and has relation more particularly to a device of this general character particularly designed and adapted for use in connection with shields for closet 15 seats in order to render the same sanitary.

An object of the invention is to provide novel and improved means whereby a plurality of shields may be maintained in a manner whereby the shields are particularly 20 adapted for use in public places.

A still further object is to provide a novel container having a relatively large opening to permit easy access to the shields or articles therein at the same time to provide 25 means to prevent the shields from falling over the edge of the opening.

The invention consists in the details of construction and in the combination and arrangement of the several parts of my improved container whereby certain important 30 advantages are attained and the device rendered simpler, inexpensive and otherwise more convenient and advantageous for use, as will be hereinafter more fully set forth.

35 The novel features of my invention will hereinafter be definitely claimed.

In order that my invention may be the better understood, I will now proceed to describe the same with reference to the accompanying 40 drawings, wherein

Figure 1 is an elevational view showing the receptacle or container as herein included, in its initial or closed position;

Figure 2 is a view in elevation illustrating 45 the receptacle or container as herein embodied in condition to be suspended, and with the shield shown partly in elevation and partly indicated by dotted lines;

Figure 3 is a sectional view taken substantially on the line 3—3 of Figure 2, and,

Figure 4 is a view in plan of a shield as comprised in the present invention.

As disclosed in the accompanying drawings, R denotes a receptacle or container 55 adapted to be supported in convenient proximity to a closet and which has applied

therein a suitable supply of shields S adapted to be singly withdrawn by a user for proper application to the seat of the closet.

As herein disclosed, each of the shields S 60 comprises a sheet 1 of paper provided with a central opening and of a design in plan to substantially entirely overlie the upper surface or face of the closet seat and the longitudinal sides of said sheet 1 are provided with the diametrically opposed and outstanding tongues 2 which afford means whereby the placing of the shield upon the seat or the removal therefrom is facilitated. I also find it of advantage to provide the 70 opposite longitudinal portions of the sheet substantially midway thereof with the weakened portions 3, preferably provided by perforations, whereby the shield if discarded within the closet bowl will separate so that 75 the possibility of sheet clogging the waste pipe as a result of a flushing operation is substantially avoided.

A receptacle or container R, preferably 80 comprises an envelope of manila or other ordinary heavy paper, and which is of a size to readily receive a plurality of shields S. Each of the shields S when applied within the receptacle or container R is folded along the weakened lines 2 and also along the line 85 indicated as a in Figure 4, so that said applied shields is substantially of a quarter formation. The shields S are also alternately applied within the receptacle or container R, as is clearly illustrated in Figure 2. 90

The receptacle or container R has the upper portion of its front face open to facilitate the withdrawal of a shield and said open portion is normally closed by the flap 4 and before the receptacle or container is 95 suspended in working position, it is preferred that the flap 4 be inserted within the envelope.

The sides of the back flap are provided with the extensions 7 which overlap and are 100 secured to the front flap 8. The upper end portions of these extensions or flaps 7 extend beyond the upper edge of the front flap 8 to provide relatively narrow guides 9 between which shields are disposed. By providing the guides 9, regardless of the size of the shield and its folded position within the container, it will be an easy matter for the user to grasp the shield and remove the same without damaging the shield in view 110 of the fact that a shield of this general character is made of very thin paper.

Each upper corner portion of the back of the receptacle or container R has secured thereto a tab or hanger 5 provided with a perforation or opening 6 so that said tab or hanger can be readily engaged over a nail or other support when it is desired to suspend the receptacle or container in working position.

Before suspending the receptacle or container R, the flap 4 is thrown back so that the tabs or hangers 5 will be unobstructed and also to permit the convenient withdrawal of the shields.

When the flap 4 is in closed position the hanger tabs 5 are forced or flexed inwardly of the container whereby it is substantially assured that the container with its contents may be transported or handled with the liability of injury avoided. In practice the flap 4 overlies the rear face of the back flap 10 to permit the tabs 5 to project beyond the upper edge of the back member or flap for proper engagement with the desired supporting means.

From the foregoing description, it is thought to be obvious that a container constructed in accordance with an embodiment of my invention is particularly well adapted for use by reason of the convenience and facility with which it may be employed and it will also be obvious that my invention is susceptible of some change and modification without departing from the principle and spirit thereof and for this reason I do not wish to be understood as limiting myself to the precise arrangement and formation of parts as herein shown in carrying out my invention in practice, except as hereinafter claimed.

I claim:

1. A container of the character described comprising a sheet of material formed to

provide a back member, one end portion of the back member being extended back upon said back member to provide a front flap, 45 the opposite end portion of said back member being extended back into engagement with the opposite face of the back member to provide a cover flap, the sides of the back member having extensions which are extended back upon the front flap and toward each other to provide end flaps, the upper end portions of said end flaps extending above the front flap to provide guides adapted to cooperate with the front flap, 55 and hanger tabs carried by the upper end portion of the back member partially beneath the upper extremities of the end flaps.

2. A container of the character described comprising an envelope including a closing flap carried by the back thereof, the upper portion of the front of the envelope being cut away, said flap when in closed position closing said cut away portion of the front, and hanger tabs secured to the inner face 65 of the back, said tabs being inwardly of the closing flap when said flap is in closed position.

3. A container of the character described comprising an envelope including a closing 70 flap carried by the back thereof, the upper portion of the front of the envelope being cut away, said flap when in closed position closing said cut away portion of the front, said receptacle being provided with end 75 flaps overlying the front flap and extending beyond the upper end of the front flap to provide guides, and hanger tabs carried by the back of the container and extending beneath the end flaps.

In testimony whereof I hereunto affix my signature.

JESSIE E. HUDGEL.
